CARL DEMPSTER HART, OF LA GRANGE, ILLINOIS, ASSIGNOR TO WESTERN ELECTRIC COMPANY, INCORPORATED, OF NEW YORK, N. Y., A CORPORATION OF NEW YORK.

METHOD OF AND APPARATUS FOR SERVING A CORE.

Application filed May 17, 1923. Serial No. 639,652.

This invention relates to a method of and apparatus for serving a core and more particularly to serving a flexible core with a relatively inflexible tape.

5 It is frequently desirable to apply a relatively inflexible serving upon a flexible core without substantially detracting from the flexibility of the core. In the case of a flexible electrical conductor covered with a soft 10 vulcanized sheathing, such as rubber, over which a plurality of relatively inflexible tapes are served in spiral formation to serve either as a protection therefor or as another electrical conductor, it is of advantage to 15 permit the flexing of the composite cable to some extent. However it is necessary to limit the amount which the cable may be flexed to prevent injury to the central conductor or the vulcanized covering therefor. 20 Furthermore it is important that no undue strains be imposed upon the soft vulcanized rubber sheathing while relatively inflexible tapes are being served thereon.

It is an object of the invention to apply 25 a tape around a core so as to permit the flexing of the taped core within predetermined limits.

Another object is to apply to a core a 30 plurality of tapes conforming to the contour of the core and separated by predetermined distances.

Another object is to minimize the localized 35 strains and pressures imposed upon a core in the application thereto of a relatively inflexible tape.

These and other objects not specifically mentioned above will clearly appear from the following description and the accompanying drawings illustrating one embodiment 40 of the invention, and in which

Fig. 1 shows an elevation, partially in section, of the essential portions of the apparatus used in practicing the invention;

Fig. 2 shows a fragmentary end view of 45 the rotating plate member through which the tapes are fed;

Fig. 3 shows an enlarged fragmentary elevation of the devices for forming the tapes and a portion of the taped core;

50 Fig. 4 shows an end view, partially in section, viewed from the dotted line 4-4 of Fig. 3;

Fig. 5 shows an enlarged end view of one

of the forming devices viewed from the dotted line 5-5 of Fig. 3;

55 Figs. 6 to 9 inclusive are sections of the core taken along the lines 6-6, 7-7, 8-8, and 9-9 respectively of Fig. 1 showing the various steps taken in applying the tapes, and

60 Fig. 10 is an enlarged section of the completely taped core viewed from the line 10-10 of Fig. 1.

65 Referring to the drawings in which similar reference characters denote similar parts throughout the various views, a serving head 15 having attached thereto a face plate 16 is rotatably mounted in any suitable manner from the floor or otherwise and adapted to be rotated by any suitable means (not 70 shown) around a centrally located tube 17. A flexible core 18 which may be of a composite type consisting of a central metallic conductor 60 (Fig. 10) surrounded by a 75 plurality of smaller conductors 61, sheathed by a vulcanized rubber insulation 62, around which a plurality of fabric tapes 63, and a thin flexible metallic tape 64 are wound, may be drawn through the tube 17 by any suitable means, such as a take-up capstan of any 80 ordinary type (not shown). At diametrically opposite points in the face plate 16 openings 20 and 21 are provided through which relatively inflexible tapes 22 and 23 85 respectively are fed from supply pads (not shown) which may be carried by the rotating head 15.

85 Arms 27 and 28 projecting from and suitably attached directly to, as well as braced 90 from the face plate by brackets 25 and 26 respectively, carry at their forward extremities devices 30 and 31 through which the tapes 22 and 23 pass. As shown more in detail in Figs. 3, 4, and 5 each of these 95 devices consists of an idler roller 32 having a slightly concave surface and secured in a mounting 34 by a screw 33 and placed in spaced opposition to the convex surface of a forming block 36 suitably attached to the mounting 34 by a plurality of screws 38. 100 The working clearance between each roller 32 and the opposing surface of the associated forming block 36 is so adjusted and the devices 30 and 31 are so located that the tape passing therethrough is given a slightly 105 transverse curvature with a permanent set

since the tape is ductile and not flexible. The tube 17 is provided with a projection 40 having an externally tapered end which receives the curved tapes 22 and 23 and directs them 5 to the core 18, passing therethrough.

Suitable die members 42, 43, and 44 having gradually decreasing internal diameters are provided for making the partially formed tapes 22 and 23 conform accurately 10 to the contour of the core without imposing any deleterious strains upon the core, the tape having a permanent set after its emanation from each die. These dies may be of any suitable type having circular openings 15 of gradually decreasing diameters to cause the tapered cores to assume in succession the forms illustrated in Figs. 7, 8, and 9. A second serving head supported by a floor bracket 50 is provided for serving over the 20 tapered core another tape or ribbon 55 of some suitable fabric impregnated with any usual insulating compound. This head is adapted to be rotated by a pulley 51 engaged by a belt 52 which may be operated from any 25 suitable source of power (not shown). A pair of spindles 53 are attached to and carried by a plate member 54 of the head. A pad 56 of the fabric tape 55 is mounted on one of the spindles and the tape is fed therefrom through the guiding fingers 58 on its 30 way to the core. The form of the completely tapered core is clearly shown in Fig. 10.

In the operation of the apparatus the core 18 is fed from a supply reel (not shown) 35 through the tubes 17 and 40, the dies 42, 43, and 44, and the central opening of the fabric tape serving device, and thence secured in some well known manner to a power driven capstan of any usual type (not shown). 40 The relatively inflexible tapes 22 and 23 of metal or other material are secured to the core in any manner and the associated serving head is caused to rotate. The core and the tapes 22 and 23 are thus drawn through 45 the dies and the rotating fabric tape serving head where they receive a spiral wrapping of the tape 55.

The devices 30 and 31 so form the tapes 22 and 23 that, as they leave the extreme end 50 of the tube 40, they present a slightly concave surface to the cylindrical core 18 as shown in Fig. 6. Also due to the width of the tape and the location of the devices 30 the edges of the adjacent tapes are separated 55 by an appreciable predetermined distance. The openings in the dies 42, 43, and 44 being circular and of gradually decreasing diameter the edges of the tapes 22 and 23 are gradually pressed toward the core as shown 60 in Figs. 7, 8, and 9 until all points of the outer surfaces of the tapes are equi-distant from the core center. Since the forming action of each die is very small no undue pressures are imposed upon the core thereby.

As the plate 54 is rotated through the

action of the belt 52 and the pulley 51, the impregnated fabric tape 55 is fed through the guiding fingers 58 and is applied to the served tapes 22 and 23 in a spiral fashion with an overlapping lay to produce an article 70 having a cross section as shown in Fig. 10.

It will be noted that the edges of the tapes 22 and 23 neither project into the core underneath nor beyond other portions of the outer surfaces of the tapes. When the tapered core 75 is flexed these edges may approach each other until they abut, but since they are equi-distant from the center of the core there is no tendency for either edge to pass under or over the other. Therefore no further 80 flexing in that direction is permissible, due to the relatively inflexible nature of the tapes. Thus by properly spacing the edges of the tapes the amount of flexure of the 85 tapered core may be so limited as to prevent the introduction of any deleterious strains into the core.

What is claimed is:

1. The method of serving a core with a metallic tape, which consists in transversely 90 forming the tape with a permanent set to approach the contour of the core, applying a concave surface of the formed tape directly to the core, and further transversely forming the applied tape with a permanent 95 set to conform to the contour of the core.

2. The method of serving a core with a tape, which consists in transversely forming the tape with a permanent set to approach the contour of the core, applying a concave 100 surface of the formed tape directly to the core, and forming the tape in a plurality of successive stages to conform to the contour of the core, the tape having a permanent set after each forming operation.

3. The method of serving a cylindrical core with a metallic tape, which consists in transversely forming the tape with a permanent set about a radius greater than that of the core, causing contact between the center line 110 of the concave surface of the tape and the core, and then further transversely forming the tape with a permanent set to conform to the contour of the core.

4. The method of serving a core with a 115 plurality of tapes, which consists in transversely curving the tapes with permanent sets, and then simultaneously serving the curved tapes in separated relation upon and with a concave surface thereof adjacent the 120 core.

5. The method of serving a cylindrical core with a plurality of tapes, which consists in transversely forming the tapes with permanent sets to approach the contour of the 125 core, engaging the center lines of the tapes with the core at points arcuately spaced to insure a predetermined separation between the edges of the tapes when conforming to the contour of the core, and then forming 130

the tapes with permanent sets to conform to the contour of the core.

6. The method of serving a cylindrical core with a tape, which consists in trans-
5 versely forming the tape with a permanent set to approach the contour of the core, applying a concave surface of the formed tape to the core, and then passing the taped core through a series of dies having openings of
10 gradually decreasing diameters to trans-
versely form the tape to conform to the contour of the core, the tape having a permanent set after its emanation from each die.

7. In an apparatus for serving a tape on
15 a core, means for transversely forming a tape with a permanent set, means for applying a concave surface of the formed tape directly to the core, and means for further

transversely forming the applied tape with a permanent set in a plurality of stages to 20 conform to the contour of the core.

8. In an apparatus for serving a core, means for applying tapes from a plurality of supplies thereof to the core in spaced relation to provide predetermined amounts of 25 clearance between adjacent edges of the tapes when conforming to the contour of the core, means for partially forming the tapes transversely before application to the core giving the tape a permanent set, and means for further forming the applied tapes 30 transversely giving the tape a permanent set, to conform to the contour of the core.

In witness whereof, I hereunto subscribe my name this 7th day of May A. D., 1923.

CARL DEMPSTER HART.
